(57) **CLAIM**

The ornamental design for a treestand hook as shown and described.

DESCRIPTION

FIG. 1 is a partial perspective view of a square tubing frame for a treestand having a treestand hook according to our new design attached thereto.

FIG. 2 is a top-front perspective view of the treestand hook according to our new design.

FIG. 3 is a bottom-rear perspective view thereof.

FIG. 4 is a top plan view thereof.

FIG. 5 is a bottom plan view thereof.

FIG. 6 is a front elevation view thereof.

FIG. 7 is a rear elevation view thereof.

FIG. 8 is a left-side elevation view thereof; and,

FIG. 9 is a right-side elevation view thereof.

Broken lines partially illustrate a square tubing frame for a treestand that forms no part of the claimed design.

1 Claim, 9 Drawing Sheets
